UNITED STATES PATENT OFFICE.

RANSOM W. DAVENPORT, OF DETROIT, MICHIGAN, ASSIGNEE TO CHICAGO PNEUMATIC TOOL COMPANY, OF NEW YORK, N. Y., A CORPORATION OF NEW JERSEY.

APPARATUS FOR REFRIGERATING SYSTEMS.

Application filed September 8, 1925. Serial No. 54,867.

This invention relates to apparatus for use in mechanical refrigerator systems with particular reference to the heat absorbing members or elements commonly designated as 5 evaporators.

It is customary to design evaporators with sole regard to the quantitative proportioning of their internal and external areas, and their internal cross section. For example, 10 steam boilers are usually designed with these points principally in mind. Likewise refrigerating boilers or evaporators are usually figured simply on the basis of total heat transferring surface.

15 This invention is particularly adapted to refrigerating systems employing working substances which are slow in evaporating, such as mixtures of liquid, vapor, and gas, and one of its principal objects is to provide 20 an evaporator adapted to be employed in the cooling of domestic refrigerators of the mechanically operated type utilizing such a working substance and providing a considerable external area for convective 25 heat transfer.

Evaporators hitherto known or used for this and other similar applications are not well suited to my purposes for many reasons. All common constructions have a 30 broken or irregular external surface—coils, stacks, finned tubes, and the like—, actually a menace to health when used for my purposes since they cannot be easily kept in a clean and sanitary condition. On the other 35 hand, all known forms in which the external surface is smooth and easily cleaned are lacking in one characteristic particularly desirable where slow evaporating substances are involved, namely, the length of travel of the 40 working substance, which is required in order that time may be allowed for the liquid to evaporate into equilibrium with the vapor.

In order to illustrate the invention one 45 concrete embodiment thereof is disclosed in the accompanying drawings in which:

Fig. 1 is a side elevational view;

Fig. 2 a vertical transverse sectional view substantially on the line 2—2 of Fig.

50 1; and

Figs. 3 and 4 are respectively a side elevational view and a plan view of one form of baffle core.

The improved type of evaporator element 55 comprising the present invention is formed,

as illustrated, of plates of sheet material, preferably of metal or other suitable heat conducting material, secured together in face to face engagement and so formed as to provide between the plates an elongate passage, conduit, or chamber, in which liquid refrigerant may be disposed. In the drawing the two plates forming the refrigerating element or evaporator are indicated by the reference characters 3 and 4. In order to 60 provide the elongate fluid passage between the plates at least one of the plates such as plate 3, has raised portions 3'. By preference, however, both of the plates forming the element have raised portions 3' and 4' 65 respectively, these raised portions being complementally disposed therein so that when the plates are assembled together in the manner shown the raised portions register in opposition so that the elongate passage is disposed partly within both plates. 70

In order to adapt the evaporator element to refrigerating systems utilizing a working substance which is slow to evaporate, such as a physical mixture of a liquid and a gas 80 substantially inert to and insoluble in the liquid, the passage formed in the element must be of considerable length to provide the necessary time factor. The evaporator of the present invention lends itself readily 85 to this requirement since the fluid passage therewithin can be made of any desired length, having regard to the dimensions of the element itself. To secure the maximum length of passage the same is preferably 90 made sinuous, doubling back and forth in transverse stretches the full width of the element, as illustrated. While the passage may be uniform in size or progressively 95 larger from end to end or with one or more progressively larger portions, it is disclosed in the drawing as differential in size, having a part b of small size adjacent the inlet 5 at the bottom of the element and a part c of larger size taking up the greater part 100 of the remainder. The upper end of the larger passage c preferably connects with, or opens into, a chamber d, also formed between the plates 3 and 4 and having therein baffle means e in the form of a core extending longitudinally of chamber d so that the latter acts as a separator chamber and prevents entrained liquid from being drawn 105 into the outlet pipe 6 which is connected to the suction side of the compressor or 110

pump (not shown) of the refrigerating apparatus.

One simple and economical method of forming the element A is to take sheet metal having the requisite strength and to form the complementary raised portions therein by stamping the plates between dies. The baffle core e, which may be of any suitable form such as a mass of spaced plates, is secured in proper position to one of the plates and then the two plates are assembled in face engagement with the raised portions thereof in opposed registration as indicated in Fig. 2. The plates may be secured together in any desired manner as by welding, soldering, and even by crimping the edges as indicated in the drawing if suitable sealing material impervious to the working substance is used to seal the plates adjacent the continuous passage formed by raised portions b and c. After the element A has been formed, its external surface may be treated, if necessary or desirable, in any desired manner to give it a smooth and easily cleaned surface, one method being to coat the exterior with vitreous enamel. One way of installing the element and connecting it into a mechanical refrigerating system is disclosed in my co-pending application Ser. No. 47,457 filed August 1, 1925 entitled Refrigerating and ice making cabinets.

Figs. 3 and 4 illustrate a preferred form of baffle core e. The core is constructed of a plurality of plates f, each corrugated with the corrugations angularly disposed relative to the sides of the plate, the plates being so disposed in face engagement that the corrugations cross each other as indicated in Fig. 3. The plates are united to form the core in any suitable manner as by having the ends thereof soldered together. Such a core provides tortuous passages for the vapor, which is drawn out of chamber d, and effectively separates from the vapor substantially all of the entrained liquid.

From the above it will be apparent that the present invention discloses a simple form of heat absorption element for use in mechanical refrigerating systems which can be easily and economically manufactured, which is adaptable to systems using working substances which evaporate slowly and require time for the vapor of the liquid refrigerant to reach substantial equilibrium in conformity with the change in temperature, and which presents a smooth exterior surface without deep pockets and inaccessible crevices thus enabling it to be easily kept in a clean and sanitary condition.

I am aware that the invention is adapted to varied conditions and uses including apparatus for condensing the vaporized refrigerant, and that such adaptations may involve departures from the specific form illustrated in the accompanying drawing

but which are within the spirit and scope of the invention. It is to be understood that such departures, modifications and adaptations are intended to be covered by the appended claims

70

I claim as my invention:

1. A member for use as an element in a mechanically operated refrigerating system comprising substantially flat plates of heat conducting material in face engagement and having their peripheral portions united, said plates providing therebetween an elongate passage.

2. A member for use as an element in a mechanically operated refrigerating system comprising two plates of sheet material in fluid-tight face-to-face engagement at least as to their peripheral portions, one of said plates being formed with raised portions providing between the plates an elongate passage.

3. A member for use as an element in a mechanically operated refrigerating system comprising two plates of sheet material secured together, both of said plates being stamped to form complementary raised portions, said plates being secured directly to each other with their complementary raised portions opposed whereby said plates cooperate to form an elongate passage therebetween.

4. A member for use as an element in a mechanically operated refrigerating system comprising plates of sheet material secured to each other in face engagement in a fluid-tight manner and providing therebetween an elongate passage differential in size.

5. A member for use as an element in a mechanically operated refrigerating system comprising two plates of sheet material secured together, one of said plates being formed with raised portions providing between the plates an elongate passage differential in size, the flat portions of said plates being placed together in face engagement and united in a fluid-tight manner.

6. A member for use as an element in a mechanically operated refrigerating system comprising relatively thin plates of heat conducting material secured together in face engagement and providing therebetween an elongate passage enlarged at one point to form a chamber.

7. A member for use as an element in a mechanically operated refrigerating system comprising two plates of sheet material secured together, one of said plates having portions raised above its plane to form between the plates an elongate passage having an enlargement or chamber adjacent one end.

8. An evaporator for a mechanically operated refrigerating system comprising plates of sheet material secured together in face engagement and providing therebe-

tween an elongate sinuous passage terminating in an enlargement or chamber, and baffle means within said chamber.

9. An evaporator for liquid refrigerant comprising two plates of heat conducting material secured together in face engagement, said plates having complementary raised portions in opposed registration forming an elongated sinuous passage terminating at the top of the evaporator in a chamber, the outlet of said evaporator being connected to said chamber, and a baffle core within said chamber intermediate said outlet and said passage to prevent liquid entrained with the vapor of the refrigerant from passing through said outlet when the evaporator is in use.

10. An evaporator for liquid refrigerant comprising two plates of sheet material secured together in face engagement, said plates being stamped to form complementary raised portions providing an elongate, sinuous passage differential in size and terminating in an enlargement or chamber, the outlet of said evaporator being connected to said chamber, and a baffle core within said chamber intermediate said outlet and said passage to prevent liquid entrained with the vapor of the refrigerant from passing

through said outlet when the evaporator is in use.

11. A thin, flat evaporator element formed of sheet material having an elongate fluid passage therein and baffle means in a portion of said passage.

12. A thin, flat evaporator element formed of sheet material and providing a fluid passage therein of substantial length, said passage being enlarged at one point to form a chamber.

13. A thin, flat evaporator element formed of sheet material and providing an elongate fluid passage therein differential in size and terminating at one end of said element in an enlargement or chamber.

14. A thin, flat evaporator element formed of sheet metal plates secured in face engagement and providing therebetween an elongate passage winding back and forth and extending substantially from end to end and from side to side of the element, said passage terminating in an enlargement or chamber adjacent the top of the element, and baffle means in said chamber.

Signed by me at Detroit, Michigan this 4th day of September, 1925.

RANSOM W. DAVENPORT.
